UNITED STATES PATENT OFFICE.

JAMES C. SHAW, OF GRAND RAPIDS, MICHIGAN.

BILL-FILE.

SPECIFICATION forming part of Letters Patent No. 562,667, dated June 23, 1896.

Application filed December 17, 1894. Serial No. 532,074. (No model.)

To all whom it may concern:

Be it known that I, JAMES C. SHAW, a citizen of the United States, residing at Grand Rapids, in the county of Kent and State of Michigan, have invented certain new and useful Improvements in Bill-Files, of which the following is a specification.

My invention relates to improvements in bill-files for use by grocers and other small traders for filing duplicate purchase-slips; and its objects are, first, to provide for so bunching the sales-slips for each individual account that the account of any individual may be readily ascertained without the necessity of journal and ledger accounts, and, second, to provide a bill-file having a series of pockets, each overlapping the other, so constructed that each pocket may be made to receive several accounts without exceeding the capacity of the file, and I attain these objects by the construction shown in the accompanying drawings, in which—

Figure 1 is a front view of my device. Fig. 2 is a top view, Fig. 3 is an edge view, and Fig. 4 is a back view, of the same.

Similar letters refer to similar parts throughout the several views.

In constructing my bill-file I take a series of sheets of paper or other suitable material and lap them one over the other, as indicated at A in Figs. 1 and 3, and secure them together by securing a strip, as a, to the back of the entire series, by which means the lower edge only of each sheet is secured to the strip, so that the strip acts not only as a support to hold the several sheets together, but the point of union between the two acts as the bottom of the pockets. I then fold each end of the sheets back and secure them to a second and broader strip or back a'', as shown at a' in Figs. 2 and 3, which strip is, or may be, securely attached to the leaves C of the file. I reinforce the upper edges of the pockets by

running a line of stitches, a cord, a binding, or other suitable reinforcement along or through the top edges, as indicated at b and B'' in Figs. 1 and 3.

B B B are representations of several parcels of sales-slips stored in the several pockets, and B' represents one parcel that is short and has slipped down entirely into the pocket, and is shown to illustrate the utility of the apertures b b, &c., in the tops of the several pockets.

The pockets may, if desired, be indexed and the accounts of individuals whose initial letter corresponds with any initial letter on a pocket inserted in such pocket; but as this means of designating the locality of an individual account is old I of course do not claim it as a portion of my invention, but simply suggest it as a convenience in connection with my invention.

Having thus fully described my invention, what I claim as new, and desire to secure by Letters Patent is—

1. In a bill-file, a series of oblong sheets lapped one upon the other, a strip secured to the backs thereof to form a support and bottoms for the pockets, and the edges of the sheets folded over and secured by an overlapping strip, substantially as and for the purpose set forth.

2. In a bill-file, a series of overlapping sheets secured by a strip at the back, the ends of the sheets bent back and united by an overlapping strip, and a folding cover to support the whole, substantially as and for the purpose set forth.

Signed at Grand Rapids, Michigan, this 12th day of December, 1894.

JAMES C. SHAW.

In presence of—

GEO. E. SHAFER,
ITHIEL J. CILLEY.
